UNITED STATES PATENT OFFICE.

CLAYTON E. GIFFORD, OF MARION, OHIO.

RADIATOR-CAP.

1,382,499.

Specification of Letters Patent. Patented June 21, 1921.

Application filed July 7, 1920. Serial No. 394,444.

To all whom it may concern:

Be it known that I, CLAYTON E. GIFFORD, a citizen of the United States, residing at Marion, in the county of Marion and State 5 of Ohio, have invented certain new and useful Improvements in Radiator-Caps, of which the following is a specification.

This invention has for its object to provide an improved cap structure which is especially designed for application to motor vehicle radiators and possesses novel features of construction enhancing the security of the fastening of the cap and facilitating its convenient opening and closing movements.

With this and other objects in view, the invention consists in certain novel features of construction as hereinafter shown and described and then specifically pointed out in 20 the claims, and in the drawings illustrative of the preferred embodiment of the invention.

Figure 1 represents a fragmental perspective view of the radiator of a motor vehicle 25 illustrating the improved cap applied thereto.

Fig. 2 represents a front elevation of the cap detached, and,

Fig. 3 represents a vertical sectional view on the line 3-3 of Fig. 2.

Referring to the drawing in detail, where-in similar reference numerals designate corresponding parts throughout the several views, the numeral 5 indicates a collar or spout which is designed to be adequately secured in the filling opening of a motor vehicle radiator 7 as by means of a depending externally threaded flange 6. The bore of the collar constitutes the filling opening for the radiator through which the latter is filled 35 with water or other liquid.

The upper edge of the spout or collar 5 is formed with an upstanding rim or flange 8 and also with diametrically opposed outwardly projecting ears 9 and 10 arranged at 40 the rear and front of the spout, respectively.

The top designated generally by the numeral 11 consists essentially in a flat substantially circular body having a rearwardly directed extension 12 provided with depending ears 13 which straddle the ear 9 and receive a pivot pin 14 whereby the cap 11 is hingedly supported at the rear portion of the spout or collar 8. The underside of the cap body 11 is formed with a circular de-

pression 15 receiving a gasket 16 adapted to 55 seat upon the rim 8 of the spout to effectively close the latter and prevent leakage of the liquid contents of the radiator.

The front portion of the cap body is provided with a forwardly directed lug 17 receiving a pivot pin 18 on which a fastening element designated generally by the numeral 19 is pivotally secured. The fastening element consists of a tubular body 20 having an apertured closed terminal 21 and spaced 60 arms 22 disposed at the end opposite 21 and receiving the pivot pin 18 whereby pivotal connection is established between the terminal of the fastening element and the cap.

The bifurcations or arms 22 of the casing 70 20 are spaced sufficiently to accommodate the lug 10 of the spout 8 when the casing is swung downwardly to operative position as illustrated in the drawing in full lines. However, when the fastening element is 75 swung upwardly the lug 10 is disengaged thereby permitting the cap 11 to be swung to open position.

The underside of the lug 10 is provided with a cam face 23 engaged by the rounded 80 head 24 of a plunger slidably mounted in the casing 20 and including a shank which extends through the apertured terminal 21 of the casing. The lower extremity of the shank externally of the casing is provided 85 with a circular head 25 for limiting the upward movement of the plunger under the influence of the spring 26 which latter is confined in the casing or housing between the head 24 and closed terminal 21. The arrangement of the cam face 23 is such that when the cap 11 is closed and the fastening element 20 swung downwardly, the spring 90 actuated plunger pressing against the cam face causes a compression of the spring 26 95 thus forcibly drawing the cap against the flange or rim 8 of the spout and establishing a tight joint. As the plunger moves upon the flat lower surface of the lug 26 the spring is maintained under compression and the housing is effectively prevented from swinging outwardly and thereby releasing the cap.

What I claim is:

1. The combination with an automobile 105 radiator including a flanged inlet thereto, of a cap overlying the flanged inlet and pivoted at one side thereof, a latch lug extending

radially of the flanged outlet, a projection extending radially from said cap immediately above and in line with said latch lug, a latch housing having its upper end 5 bifurcated to span the projection of said cap and pivoted thereto, and a latch member carried in said housing and adapted for engagement with the under face of said latch lug, when said latch housing is swung 10 to operative position.

2. In combination, a supporting member, a cap pivotally secured thereto, a fastening element pivotally secured to the cap, said fastening element including a plunger and 15 a spring actuated means therefor, and an outwardly directed latch lug carried by the supporting member and adapted to be engaged by the plunger to maintain the spring means under compression whereby to retain 20 the cap in closed position.

3. In combination, a supporting member, a cap hingedly secured thereto, a fastening element pivotally secured to the cap, said fastening element including a spring actuated 25 plunger, and an outwardly directed lug carried by the supporting member provided with a cam face engageable with the plunger whereby the latter is compressed during its movement to operative position and a flat 30 face on the lug engageable by the plunger to maintain the latter under compression and retain the cap closed.

4. In combination, a supporting member, a cap hingedly secured thereto, a fastening 35 element pivotally secured to the cap, said fastening element including a spring actuated plunger, and an outwardly directed lug carried by the supporting member provided with a cam face adapted to compress 40 the spring actuated plunger during movement of the fastening element to operative position, said fastening element being capable of being swung to inoperative position when the cap is closed, said lug having a 45 flat underside for engagement with the plunger to prevent the latter from swinging out of operative position.

5. In combination, a supporting member, a cap hingedly secured thereto, a housing 50 having a bifurcated extremity pivotally secured to the cap whereby the housing may be swung to inoperative position, a lug projecting outwardly from the supporting member engageable between the bifurcations of 55 the housing, and a spring actuated plunger mounted in the housing engageable with the lug to maintain the cap in closed position.

6. In combination, a supporting member, a cap hingedly secured thereto, an extension 60 pivotally secured to the cap and movable to inoperative position relative thereto, a housing having a bifurcated extremity pivotally secured to said extension, a lug carried by the supporting member adapted to be received 65 between the bifurcations of the hous-

ing when the latter is moved to operative position, and a spring actuated plunger mounted in the housing, said lug having a cam face adapted to coact with the plunger to compress the latter as the housing is moved to operative position. 79

7. In combination, a supporting member, a cap hingedly secured thereto, an extension carried by the cap, a housing having a bifurcated extremity pivotally secured to the 75 extension, a lug formed on the supporting member having a cam face and a flat underside, said housing having the opposite end closed, and a spring actuated plunger mounted in the housing provided with a rounded 80 terminal arranged to engage the cam face whereby the plunger is compressed as the housing is moved to operative position to lock the cap in position upon the supporting member. 85

8. The combination with an automobile radiator including a flanged inlet thereto, of a cap overlying the flanged inlet and pivoted at one side thereof, a latch lug extending radially of said flanged inlet and 90 having its free end curved to provide a downwardly extending cam face, a projection extending radially of said cap member immediately above and in line with said latch lug, a latch housing having its upper 95 end bifurcated to span the projection of said cap and pivoted thereto, and a resilient latch member carried in said housing and adapted to be moved into locking engagement with said latch lug by the cam face of the latter 100 when said housing is swung downwardly into operative position.

9. The combination with an automobile radiator including a flanged inlet thereto, of a cap overlying the flanged inlet and 105 pivoted at one side thereof, a latch lug extending radially of said flanged inlet and having its free end curved to provide a downwardly extending cam face, a projection extending radially of said cap member immediately above and in line with said latch lug, a latch housing closed at one end and 110 having its other end bifurcated to span the projection of said cap member and pivoted thereto, and a latch member resiliently seated 115 in the closed end of said housing and adapted to be moved into locking engagement with said latch lug by the cam face of the latter, when the housing is swung downwardly into operative position. 120

10. The combination with an automobile radiator including a flanged inlet thereto, of a cap overlying the flanged inlet and pivoted at one side thereof, a latch lug extending radially of said flanged inlet and 125 having its free end downwardly and inwardly curved to provide a cam face, a projection extending radially of said cap member immediately above and in line with said latch lug, a cylindrical latch housing 130

having its outer end closed and its inner end bifurcated to span the projection of said cap and pivoted thereto, and a latch member seated within the closed end of said housing and having a curved head portion adapted for coöperation with the cam face of said latch lug, whereby the same is moved into

locking engagement with the latch lug when the housing is swung downwardly into operative position.

10

In testimony whereof, I affix my signature hereto.

CLAYTON E. GIFFORD.
